UNITED STATES PATENT OFFICE.

LESTER KAUFMAN AND FRANK HERBERT FOG, OF NEW YORK, N. Y.

VEHICLE TOY DEVICE.

Application filed May 27, 1927. Serial No. 194,643.

This invention relates to a new and amusing device in the nature of a vehicle toy, particularly adapted for use by children for the purpose of providing a means of locomotion.

5 The object of the invention is to provide a vehicle toy of novel construction, and arrangement of parts, hereinafter more fully described, claimed and illustrated in the accompanying drawing.

10 Fig. 1 is a perspective view of a toy constructed according to this invention.

Fig. 2 is an enlarged vertical central sectional view thereof.

15 Fig. 3 is a fragmentary horizontal sectional view, taken on the line 3—3 of Fig. 2.

Fig. 4 is a sectional view, taken on the line 4—4 of Fig. 2.

Fig. 5 is a vertical sectional view, taken on the line 5—5 of Fig. 3.

20 Fig. 6 is a fragmentary, partly sectional detail view of the connection between the brake operating rods.

The reference numeral 10 indicates generally the body of a toy simulating a horse or 25 other animal of hollow construction, and having back legs 11, front legs 12, a movable head 13, and a movable breast 14. A casing 15 is secured within the body 10, and rotatably supports a shaft 16, having gears 17 30 fixed thereon by pins 18 passing through collars 19 integral with the gears. A brake wheel 20 is fixed on shaft 16 also, and is engageable by a brake band 21, held at one end by rod 22, supported in the casing 15, and at 35 the other end pivotally engaging a brake rod 23. Clutching face members 24 are fixed on the shaft 16 by pins 25 and are engageable by complementary clutching face members 26 urged into engagement by springs 27 loosely 40 mounted coaxially on shaft 16. The teeth of the clutching members are so formed as to engage when turned in one direction, and slip past each other when turned in the other direction. Arms 29 project from members 45 26 and the free ends of the arms connect with cords 30 passed beneath idlers 31 on shaft 32 rotatably supported in the casing 15. The cords then extend over idlers 33 and 33', and through apertures 34 in the casing 15 and 50 body 10. Foot rests 35 are secured to the ends of the cords. A spring 36 acts between the top of the casing 15 and the levers 29, urging the levers into an uppermost position. Each of the legs 11 are provided with wheels 55 37 fixed on a rotatable shaft 38 between the

legs. Gears 39 fixed on the shaft are connected by chains 40 to the gears 17.

The legs 12 are provided with wheels 41 fixed to the bottoms of shafts 42 rotatable in the legs 12. The interior of body 10 is provided with bosses 43 and levers 44 rest on the bosses and are fixed to the tops of shafts 42. A bridge member 45 extends across the bosses 43, and the breast member 14 is pivoted at 46 to this bridge member. The numeral 14' in Fig. 4 illustrates that the lower portion of the breast member 14 is of curved contour so as to engage around the bosses 43 and extend beneath the pivot point 46. The ends of levers 44 are pivotally connected to a cross rod 47, urged by obliquely arranged springs 48 into a central position. A rod 49 has a lower pivoted section 49' pivotally secured to the center of cross rod 47 and the rod 49 extends upwardly into the head 13, and is connected to a top section 49^a by means of a pin 49^b projecting from the rod 49 and slidably engaging in a slot in the section 49^a, the section 49^a being secured to a cross rod 50 secured to the said head 13.

The brake rod 23 has a hollow end which telescopically connects with a rod 51 and an expansion spring 52 acts between flange 23' on the rod 23 and collar 51' on the rod 51, and serves to communicate motion from one rod to the other. The end of rod 51 remote from the telescopic connection is pivotally connected to rod 49 intermediate the ends thereof, and a limiting rod 52 is pivotally connected to rod 49 to engage a limiting collar 53 depending from casing 15, so as to restrain spring 52 from moving rod 49 further than desired. The head 13 is connected to the body 10 by a universal joint 54. A saddle 55 is disposed on the body of the animal, and reins 56 connect with the head 13.

The operation of the toy consists of the user thereof sitting on the saddle 55, engaging his feet in foot rests 35 and periodically depressing the foot rests to cause the motion to be transmitted to the levers 29, forcing the levers downwards, and thus causing shaft 16 to turn. The rotating motion is communicated to wheels 37 by the chains 40, and the toy moves forward. Should the rider wish to stop the device he pulls on the reins 56 moving head 13 upwardly about pivot 54, thus moving rod 49. The motion is communicated to rod 51 thereafter to braking rod 23, and brake band 21, causing the device 110

to stop. While the device is moving the rider may steer to the right or left, by pulling the reins so as to turn the animal's head 13, to the right or left. Moving the head 13 to the right or left moves the rod 49 similarly and the motion communicates with the cross rod 47, the levers 44, the rods 42, and finally the wheels 41.

While we have illustrated and described 10 the preferred form, construction, and arrangement of the several elements employed, it will be understood that the device is, nevertheless, susceptible of considerable modification therein, and we therefore reserve the 15 right and privilege of resorting to all such changes as may be fairly embodied within the spirit and scope of the invention as claimed.

Having thus described our invention, what 20 we claim as new and desire to secure by United States Letters Patent is:

1. In a device of the class described, the combination with a brake wheel on a driving shaft of the device, of a braking band engageable with the wheel, a braking rod connected with the braking band, another rod in telescopic connection with the braking rod, an expansion spring, normally urging the rods apart, the second mentioned rod being 25 connected between the ends of a rod, an animal's head associated with the device, and the last mentioned rod being movable to operate the brake when the animal's head is tilted upwardly.

2. In a device of the class described, the combination with a brake wheel on the driving shaft of the device, of a braking band engageable with the wheel, a braking rod connected with the braking band, at one end 30 thereof, the other end of the band being connected to a stationary part, another rod in telescopic connection with the braking rod, an expansion spring normally urging the rods apart, the second mentioned rod being 35 connected between the ends of a rod, an animal's head associated with the device, and

the last mentioned rod being movable to operate the brake when the animal's head is tilted upwardly.

3. In a device of the class described, the combination with a brake wheel on the driving shaft of the device, of a braking band engageable with the wheel, a braking rod connected with the braking band, at one end 50 thereof, the other end of the band being connected to a stationary part, another rod in telescopic connection with the braking rod, an expansion spring connected between the rods, and normally urging the rods apart, the second mentioned rod being connected between the ends of a rod, an animal's head associated with the device, and the last mentioned rod being movable to operate the brake when the animal's head is tilted upwardly. 55

4. In a device of the class described, the combination with a brake wheel on the driving shaft of the device, of a braking band engageable with the wheel, a braking rod connected with the braking band, another rod in telescopic connection with the braking rod, 60 a means for normally urging the rods apart, the second mentioned rod being connected between the ends of a rod, an animal's head associated with the device, and the last mentioned rod being movable to operate the brake 65 when the animal's head is tilted upwardly.

5. In a device of the class described, the combination with a brake wheel on the driving shaft of the device, of a braking band engageable with the wheel, a braking rod connected with the braking band, another rod in telescopic connection with the braking rod and resiliently connected therewith, the second mentioned rod being connected between the ends of a rod, an animal's head associated with the device, and the last mentioned rod being movable to operate the brake 70 when the animal's head is tilted upwardly. 75

In testimony whereof we have affixed our signatures.

LESTER KAUFMAN.
FRANK HERBERT FOG.
